UNITED STATES PATENT OFFICE.

WILLIAM L. DUNN, OF PIRU, CALIFORNIA, ASSIGNOR TO DUNN MANUFACTURING COMPANY, OF OXNARD, CALIFORNIA, A CORPORATION OF CALIFORNIA.

UNDERREAMER.

1,217,086.

Specification of Letters Patent. Patented Feb. 20, 1917.

Application filed January 23, 1911. Serial No. 604,261.

To all whom it may concern:

Be it known that I, WILLIAM L. DUNN, a citizen of the United States, residing at Piru, in the county of Ventura and State of California, have invented a new and useful Underreamer, of which the following is a specification.

This invention relates to the class of well-drilling tools of the so-called churn drilling type in which the tool is reciprocated vertically in the hole.

In the drilling of wells for oil and water, etc., it is often necessary to put in long strings of pipe, sometimes as much as four thousand feet of one size of pipe in one string in order to complete a well; and it is desirable to put in as much pipe of one size as possible before reducing the size of the hole by putting in a smaller diameter of pipe.

To do this it is necessary to have an underreamer tool that will pass down through the pipe and expand underneath the pipe to a diameter large enough to make the hole underneath the pipe of sufficient diameter to allow the pipe to descend. This becomes necessary in cases where one part of the formation is soft and liable to cave in and run into the hole and when another part thereunder is comparatively hard or is very hard so as to form a support for the pipe; which support must be reamed out before the pipe will go down.

Underreamers of the reciprocating type have heretofore been constructed for this purpose, but in their use it is often found that there is a liability of reaming what is termed a flat hole, that is to say, a hole that is oblong in cross section; and where such flat reaming occurs the pipe will not go down and will become wedged in the hole, thus causing much trouble and expense because the pipe becomes squeezed flat, the heavy steel shoe sometimes splits and comes loose from the pipe thus requiring to be drilled out or causing the loss of the hole.

The formation of flat holes has been avoided in working with the reamers heretofore known by providing another tool known as a ratchet or swivel socket which forces the underreamer to rotate in the hole to some extent during the reciprocating action. Such sockets are very expensive and they wear out and get out of repair very eas-

ily; this being caused by sand getting into the ball bearing parts and the ratchet parts of the swivel socket and grinding them away.

An object of this invention is to provide an underreamer of the reciprocating type to be used in churn drilling, which will not under any circumstances drill a flat hole; thus doing away with the necessity of the ratchet or swivel socket for turning the tool.

It also often occurs with underreamers heretofore known, that as the underreamer proceeds through a practically solid but comparatively soft formation the reamed hole will be rifled; that is to say, two oppositely disposed ridges will be left between the spiral grooves which are cut by the two cutters of the underreamer and these ridges are so solid and strong as to prevent the tool from turning in the hole. But the driller is unable to determine whether or no the hole has been rifled. If the hole has been rifled, such rifles will prevent the underreamer from turning when solid formation is again encountered and a flat hole through the solid formation would result.

In order to overcome this difficulty with former reciprocating underreamers it is necessary for the driller to pull back and re-underream through the soft formation so as to insure that the underreamer will rotate during the operation of underreaming through the hard formation below.

An object of this invention is to do away with the liability of any difficulty thus arising.

Other objects of the invention are: strength; cheapness; simplicity; ease of operation; ease of inserting into and withdrawing from the hole; and durability.

Heretofore the standard reciprocating well-tools known as underreamers and operable for reaming out the hole beneath a well-casing have invariably terminated in cutters the cutting edges of which are relatively movable only in alined paths; there being only two of such cutters to each tool and the edges of such tools being movable relatively only directly toward and from each other.

Such construction of the tool is the cause of reaming flat and rifled holes for the reason that with a tool so constructed, the directing forces that result from the contact

of the cutting edges with the wall of the hole on two faces diametrically opposite each other, tend to prevent the tool from turning responsive to the twist of the cable 5 from which the tool is suspended, and the extent to which the tool will rotate at each reciprocation will not be sufficient to cause the cutters to cut out all material between verticals drawn from the ends of the cutting edges when the tool is at rest, and consequently the hole is underreamed only on two oppositely disposed sides, and between such sides there are left two ridges, so that the hole thus worked on will be only partly 10 underreamed and will be what is termed a flat and rifled hole. By providing a reciprocating underreaming tool with three or more cutters, the directing forces will not be such as to prevent the twist of the cable from turning the tool sufficiently as it is reciprocated, so that it will cut away material entirely around the hole and by arranging the cutter so that as the tool expands and contracts the cutting edges move 15 in relatively angular paths and by supplying as many cutters as can be accommodated under this arrangement in the lower end of the tool body, the interspaces between the cutter edges are minimized, and by 20 providing more than two cutters each having a cutting edge the radius of which equals the radius of the underreamed hole, and the ends of which edges practically contact with each other when the tool is collapsed to the diameter of the casing under which the hole is to 25 be reamed, the cut effected by the reciprocating tool in operation will invariably be truly cylindrical because the contact of the tool at three or more symmetrically disposed 30 lines around the axis of the tool center the tool and the drilling of a so called flat hole will be avoided. By this means I dispense with the expensive ratchet socket.

In order to provide an underreamer which 35 will invariably ream a round hole that will allow free descent of the pipe, I provide an underreamer having more than two cutters; and while expanding or contracting said cutters move relatively in paths that are in angular relation to each other and that are radial relative to the axis of the underreamer.

In carrying out this invention three or 40 more cutters must be employed and they are constructed and arranged to practically nest together when they are retracted for the purpose of passing through the pipe below which the reaming is to be effected, and to practically cover the entire circumference 45 of a circle equal in diameter to the extreme spread of the cutters, when the tool is in operation.

In the preferable form of my invention, I 50 provide a reamer with four knives or cutters which very readily pass down through

the pipe and when expanded underneath the pipe almost fill the entire diameter of the hole.

Another difficulty to be guarded against is the liability of the tempered steel cutters 55 to become detached from the body of the underreamer and lost in the hole. When thus lost in the hole it is a very serious matter, as the cutters are very difficult to fish out and almost invariably must be worn out bit by bit, which is a very expensive operation; and sometimes the cutters become driven into the formation, thus allowing the string of tools to pass, and then the cutters fall on top of the tools and wedge 60 the tools in the hole, thus causing the loss of the hole.

An object of this invention is to eliminate all danger of losing the cutters in the hole and to so construct the mandrel and other 65 parts that there is practically no possibility of any part breaking in such a manner as to allow the cutters to drop into the hole.

Another great fault with underreamers that are only provided with two cutters 70 as they are now made and used, is that when they wear a little out of gage and get some worn surface on the edge of the cutters they will often bind and stick in the hole.

This necessitates running the machinery 75 at accelerated speed in order to whip or jerk the reamer loose and it sometimes occurs that after the reamer has thus been jerked loose it is impossible to stop or slow down the speed of the engine quickly enough 80 to hold the tools out of the way and from plunging back with great force, and such plunging force is often sufficient to break the cutters in the well.

Practical well drillers have come to recognize this as one of the greatest dangers of attempting to use underreamers.

An object of this invention is to so construct the reamer as to avoid this trouble and danger; and in order to accomplish this 90 the bearings of the cutters are stepped and tapered and fitted into a stepped and tapered box in the body of the reamer and are held in the box by the spring operated mandrel; and if the cutters should have a tendency to bind or stick, the body of the reamer will 95 on the upstroke, lift up off of the tapered parts or bearings of the cutters, thus immediately releasing the cutters and allowing them to contract and thus become loose from the walls of the hole.

Another great advantage to be attained by my newly invented reamer having more than two cutters, is that if the reamer has passed down the hole for any distance below the 100 pipe, it is certain that the pipe will also pass down the same distance without any liability of flattening the pipe. This feature of improved operation is one not heretofore attained by any under-reamer and results in a 105

great saving of time and greatly increased safety with which the pipe can be let down into the well.

A further object of this invention is to provide an under-reamer, the body of which will have a longer life than the bodies of under-reamers heretofore known, and which can be fitted with stock cutters of uniform shape, made from a templet, so as to avoid the present necessity of taking the body of the reamer to the shop to fit it with cutters.

Another object is to so construct the tool as to minimize the wear between the body of the tool and the shanks of the cutters.

15 The body of this under-reamer differs from under-reamer bodies heretofore known in that it terminates at its lower end in an uninterrupted circular edge or rim inside of which is provided a stepped bowl-like cavity 20 tapering from various angles from mouth to tip in which the cutters having shoulders practically fitting the inside of the casing under which the reaming is to take place are seated and the cutters nest with and mutually support each other against inward thrust during operation; and the cavity is of such form that the downward thrust on the cutters is made by the solid portion of the body and does not jam or wear the edge 25 of the body and the body is subject to but little wear where it contacts with the cutters.

30 A further object of the invention is to so construct the cutters and the body which carries the same, that the cutters will act smoothly and respond readily to the adjusting pressures for moving the cutters into and out of their seat in the body and to provide for relatively great radial movement of the cutters.

40 The accompanying drawings illustrate the invention.

Figure 1 is a view of the underreamer as it appears descending through a well casing below which the reaming is to be effected.

45 Fig. 2 is a fragmental detail showing the lower end of the underreamer in operation below the casing shown in Fig. 1.

50 Fig. 3 is a view partly in vertical mid-section of a four-cutter underreamer as normally collapsed in a casing which is of reduced diameter just below to indicate the capability of the tool to further collapse. The mandrel and the mandrel spring are intact and two of the cutters are sectioned in the 55 axial-plane of the underreamer.

Fig. 4 is a view looking up at the bottom of the tool when collapsed in the casing, as shown in Figs. 1 and 3.

60 Fig. 5 is a plan section on line x^5 , Fig. 3. Fig. 6 is a plan section on line x^6 , Fig. 3.

Fig. 7 is a plan section on line x^7 , Fig. 3.

Fig. 8 is a fragmentary sectional view showing the underreamer expanded and in practical use.

Fig. 9 is a view looking up from the bottom of Fig. 8.

Fig. 9^a is a view of the bottom of the body.

Fig. 10 is a view of the mandrel and two of the cutters detached. The eye bolt for pulling the mandrel down to collapse the tool is also shown.

Fig. 11 is a plan of the ring for holding the cutters collapsed to enter the casing.

Fig. 12 is an axial section on line x^{12} , Fig. 14 of a form of the invention in which the under-reamer body is closed at the upper end.

Fig. 13 is a cross-section on line x^{13} , Fig. 12 looking up.

Fig. 14 is a plan section on line x^{14} , Fig. 12.

Fig. 15 is an elevation of the mandrel of Fig. 12 detached.

Fig. 16 is a view of the bottom of the body shown in Fig. 12.

15 The under-reamer illustrated by Figs. 1 to 9, inclusive, comprises a body 1 having a longitudinal bore forming the mandrel way 2 and provided at its lower end with a box 3 having a downwardly flaring or upwardly reduced or tapered stepped seat 3 to receive the upwardly reduced or tapered upper ends or shanks 4 of the assembled cutters 4. Said cutters are nested in the seat 3 and are held therein by a mandrel 5 which works in the 20 mandrel way and pivotally engages the cutters to hold their shanks seated in the box. Said cutters project below said body and form the lower end of the tool.

25 The seat 3 and the shanks of said cutters are correspondingly reduced in diameter, and the innermost faces of the cutters are so bent and the cutters are so pivoted on the mandrel that when the cutters are held up in the seat, their shanks are held compactly 100 together and the blades or lower ends of the cutters are spread apart; and when the cutters are lowered in the seat, their blades may be collapsed or nested together to such extent 105 as to allow the cutters to pass through a casing of any diameter that the body 1 will 110 pass through.

30 The mandrel 5 is yieldingly upheld by the mandrel spring 6 mounted in the enlarged spring chamber 7 of the mandrel way, and 115 is secured by nuts 8, 9, on the upper end of the mandrel.

35 The mandrel is preferably formed with a cylindrical stem 10 at the upper part and said stem works through the spring. The stem is angular in cross section at the lower portion 11 which works in the lower part of the mandrel way 2 that practically corresponds in cross section to the lower portion 120 of the mandrel; thus to hold the mandrel from turning in the body. The mandrel is 125 preferably a steel forging provided at its lower ends with four pivots 12 to engage in

seats 13 in the inner sides of the cutters 4, and is made of a single piece with such pivots.

The inner side of each cutter is constructed in two plane faces 14, 15, angularly arranged relative to each other so that the cutters will swing on the pivots 12; there being a fulcrum edge *a* between said faces at the top margin of the seat 13 between the shank 10 and blade of each cutter.

The angle between the inner faces 14 and 15 of the shank and blade is such that in the upright tool, the inner face 14 of the shank is vertical when the reamer is expanded, and the inner face 15 of the blade is practically vertical when the reamer is collapsed.

The cutters are interchangeable, all being made alike and are appropriately dressed at the lower end so as to form the bottom face 16 and the outer face 17 at such an angle with each other as to produce the cutting edge 18 which comes into play when the tool is expanded.

25 The outer faces 17 of the cutter blades are practically cylinder segments having about the same radius as the whole to be underreamed and each segmental outer face extends upward from the cutting edge 18 for a distance that may be about one-half of the whole length of the cutter from cutting edge to tip of the shank.

At the upper ends of the cutter blades and about midway between the ends of the cutter the outer face of the cutter is provided with a bulge forming a rider 20 which is a segmental frusto-conical side extension, the base of which is practically of the same radius as the normal interior of the pipe or casing 19 beneath which the underreamer is to ream.

45 The stepped seat 3 in the body is provided internally intermediate its ends with an annular sloping shoulder 21 against which the rounded tip 22 of the cutter shank may impinge under the impulse of the mandrel spring after the mandrel has been drawn down through the body so as to allow the base of the rider 20 to contact with the inside 50 of the casing.

The sloping shoulder 21 is of greater width than the rounded tip 22 of the cutter. The mandrel; the body; the sloping shoulder 21 of the seat; and the tips 22, 55 lower inner faces 15 and riders 20 of the cutters, are relatively so arranged that while the tips are in contact with the shoulder the riders may be moved outward to contact with the inner wall of a well casing of considerably greater diameter than the body; said tips being capable up and down on said shoulder, so that said riders may move in and out to follow the irregularities of the casing in which the body is being lowered or

raised while said cutters are held in collapsed position on the mandrel by contact of the tips with the shoulder and of the riders with the casing down or up which the body may move.

The body 1 is of a diameter somewhat smaller than the casing 19 for which the underreamer is designed, so as to afford the usual clearance required to allow free vertical movement of the body in the casing; and the bases of the riders are between the cutting edges and the pivotal points and edges of the cutters.

By reason of the stepped form of the seat 3 and the reduced forms of the upper ends of the cutters, considerable play is provided for the reduced tips of the cutter shanks on the shoulder 21 when the cutters are only collapsed to the extent shown in Fig. 3 where the bases of the riders 20 contact with the normal interior of the casing.

It sometimes occurs from various reasons that the bore of the casing is contracted; and in such a case, if the bases of the riders impinge upon the contracted portion; then, upon descent of the tool in the casing, the cutters would thereby be squeezed toward each other at their lower ends, thus bringing the reduced upper ends of the cutters downward and outward into the flaring mouth of the seat 3, thereby allowing the tool to abnormally collapse to the dotted position in Fig. 3; the bases of the riders being thus retracted toward the mandrel, the cutters may pass through any space through which the body 1 may pass although normally the riders slide on the inner wall of the casing and tend to center the tool therein. In this operation the spring 6 allows the cutters to move downward relative to the body so that the abnormal collapsing may occur, and return the cutters to the normal collapsed position shown in solid lines in Fig. 3, as soon as the restricted bore or indentation *d* of the casing is passed.

The box of the sub 23 in the forms shown in Figs. 1, 3 and 8, is recessed to accommodate the mandrel when the cutters are expanded as shown in Fig. 8.

The spring will normally be of such length that when the body, cutters and mandrel are assembled as shown in Fig. 8, and before the body is screwed into the sub, the nut 8 may be started onto the mandrel and may then be screwed down sufficiently to give the tension required to hold the cutters in their seats when the tool is suspended. Then the jam nut 9 may be screwed home and sufficient play is left between the nut 8 and the pin *e* of the body to allow the mandrel to be drawn down far enough to fully collapse the tool in the position indicated by dotted lines in Fig. 3. When the

nut 8 is stopped by the end of the pin 9, the cutters are still held in such position that they cannot be withdrawn from the pivots and the seat.

5 It is therefore necessary in the forms shown in Figs. 1, 3 and 8, that the body shall be unscrewed from the sub 23 whenever it is necessary to remove the cutters for sharpening.

10 In some instances, as in the case of very large and heavy reamers, it is desirable to take out the cutters to resharpen them without having to take the body of the underreamer from the string of tools and it is 15 also desirable that the pin of the underreamer body shall not be bored, thus to allow the use of the standard size tool pin 25 on the body.

Figs. 12, 13, 14 and 15 show the form of 20 construction designed to allow the cutters to be removed and replaced while the body is carried by the string of tools.

In this form the mandrel bore 24 is cylindrical and of one diameter from end to end 25 and terminates short of the pin 25; and the body 26 is provided with counter-sunk transverse bores 27 ready to receive set screws 28 and between said transverse bores and the seat 3 a transverse key-way 29 is provided to receive a key 30; and the body 26 is cut away at both sides of the key-way and on both sides of the body to form recesses 31 to accommodate pins 32 that hold the key in place. The mandrel 33 is provided at its lower end with the pivots 12 the same as in the other forms and above 35 said pivots is provided with a flat faced shank 34 to fit between the cutters 4 that correspond to the cutters shown in the other 40 views. Above the flat-faced shank 34 the mandrel is provided with a cylindrical enlargement 35 having a longitudinal slot 36 the length of which is greater than the width 45 of the key 30 so that when the mandrel is in the bore and the key 30 is in place in the body and extending through the mandrel, the mandrel can be drawn down only far enough to allow the cutters to fully collapse.

50 In order to allow the shanks of the cutters to be removed from the seat 3, the key must be removed.

A spring seat 37 in the mandrel fits the bore 24 and is provided with two recesses 55 38 into which the ends of the set-screws 28 may be screwed to hold the spring seat from moving along the bore.

The spring 6 is secured on the mandrel by the nuts 8 and 9 as in the form shown 60 in Figs. 3 and 8.

The usual open ring 39 is provided to hold the cutters in the nested position shown in Figs. 1 and 3 until they have been inserted into the casing.

The mandrel is provided with the usual 65 socket 40 for the eye bolt 41 by which the mandrel can be drawn down to allow the cutters to be removed.

In practice, when it is desired to sharpen the cutters, the key 30 will be removed, the 70 bolt 41 will be screwed into the socket 40 and force will be supplied to pull the cutters down far enough to allow them to be removed from the mandrel and the seat.

When the cutters have been sharpened, 75 they may be replaced and nested together, as shown in Figs. 1 and 8, and the open ring 39 be slipped over the cutters to hold them in their nested position preparatory to inserting them into the pipe or casing 19, and 80 when after the cutters are lowered into the casing, the ring 39 is intercepted by the top of the casing and may then be drawn off at the reduced portion 42 of the body, then the tool may be lowered into operating position 85 below the casing.

When the cutters are nested together, they practically cover the entire cross-sectional area of the casing 19, and when they pass below the bottom of the casing, they move 90 radially relative to the axis of the underreamer and in divergent relatively angular paths to the expanded position shown in Figs. 12 and 8, where they cover a maximum portion of the cross-sectional area to 95 be reamed out under the casing and therefore, the under-reaming is effected in such a way as to avoid the objections hereinbefore stated.

As clearly seen in Figs. 1, 2 and 3, 9^a and 10 16 the lower end of the box 1 is free from any side slots or openings into the box which terminates in an unbroken rim 14 and has the conical chamber or cavity 3 which forms the seat for the shanks. By reason of this 105 construction, there is practically no liability of wear between the shanks of the cutters and the end of the box, and consequently the body will outlast a great number of cutters, and the expense and loss of time required with other reamers to send the body to the shop to have the cutters fitted to it is 110 done away with.

Furthermore, by reason of the conical 115 shape of the cavity, and the shanks of the nested cutters yielding held therein, the body is adapted to lift off of the cutter shanks in case the cutters become stuck in the hole, and to allow the cutter blades to collapse and withdraw from the walls of 120 the hole so that liability of any sticking of the tool in the hole is minimized.

Owing to the construction shown whereby the tips of the shanks are adapted to rest on the intermediate sloping shoulders 21 when 125 the tool is collapsed, and at the same time the riders can ride along the casing the expansion and contraction of the cutters as

they pass out of and into the casing is effected with a smoothness of action that avoids sticking and to the efficiency and wearing qualities of the tool; and furthermore the tip resting on the intermediate shoulder relieves the riders from excessive pressure against the casing, thus allowing the use of a strong retracting spring 6 with minimized friction on the casing and gradual reduction from the mouth to the seat of the bore, gives smoothness of action and avoids jerks and jars as the cutters are brought from expanded to collapsed position, and vice versa.

15 I claim:

1. A reciprocating under-reamer provided with more than two cutters the blades of which are adapted and arranged to move radially relative to the axis of the under-reamer and in divergent relatively angular paths substantially as and for the purpose set forth, and a body provided in its lower end with a seat; said cutters projecting below said body and having shanks that nest in the seat when the tool is expanded.

2. A reciprocating under-reamer provided in its lower end with a seat and with more than two cutters having shanks in the seat and having blades that project down from the body and are radially movable in divergent relatively angular paths, and that practically nest with each other when re-

tracted substantially as and for the purpose set forth.

3. The reciprocating under-reamer set forth provided with four cutters having blades forming the lower end of the tool and adapted to practically nest together when retracted for the purpose of maximizing the cutting area when expanded, said cutters 40 being radially movable in divergent relatively angular paths.

4. The combination with a body having a longitudinal bore, an end seat and a transverse slot; of a slotted mandrel in the bore; cutters pivoted to the mandrel and having shanks in the seat; a key in the slot of the body and mandrel to limit the movement of the mandrel, and means to yieldingly hold the mandrel to seat the cutters in the seat.

5. A reciprocating under-reamer provided with more than two cutters in pivotal relation with each other, that form the lower end of the tool, the blades thereof being capable of practically nesting together when the tool is collapsed.

In testimony whereof, I have hereunto set my hand at Los Angeles, California, this 17th day of January 1911.
